UNITED STATES PATENT OFFICE.

HARRY O. RUGH, OF SANDWICH, ILLINOIS, ASSIGNOR, BY MESNE ASSIGNMENTS, TO
HAEL SWITCH & SIGNAL COMPANY, A CORPORATION OF MAINE.

SUBSTATION SIGNALING APPARATUS.

1,105,842.

Specification of Letters Patent.

Patented Aug. 4, 1914.

Application filed December 14, 1911. Serial No. 665,738.

To all whom it may concern:

Be it known that I, HARRY O. RUGH, a citizen of the United States, residing at Sandwich, in the county of Dekalb and State 5 of Illinois, have invented a certain new and useful Improvement in Substation Signaling Apparatus, of which the following is a full, clear, concise, and exact description, reference being had to the accompanying 10 drawings, forming a part of this specification.

My invention relates to signaling systems and is more particularly concerned with the arrangements of a substation signal receiving 15 device.

The invention more particularly relates to such signaling systems in which a plurality of substations are all associated with the same line circuit and in which any station 20 may be called to the exclusion of the other stations.

My invention finds its greatest usefulness in connection with step-by-step signaling systems, although it is not so limited.

25 My invention is designed to provide for a substation signal receiving device, certain slow acting means which in combination with the other elements of the device control the operation of the substation signal.

30 One form of my device contemplates the provision of suitable electromagnetic means to control a local signal circuit and the addition to the movable member of the electromagnetic means of a suitable slow acting 35 element in the form of a pneumatically controlled device to retard the operation of the circuit controlling element under the control of said electromagnetic means.

I will describe my invention more in detail by reference to the accompanying drawing, illustrating one form thereof, in which:

Figure 1 diagrammatically illustrates a signaling system arranged in accordance with my invention, and Fig. 2 is a detail 45 view of my improved delaying means.

Referring more particularly to Fig. 1, I show a central station A and two substations B and C, all united by means of a line circuit comprising the conductors 1 and 2. 50 The signal receiving device at the substation is associated by means of conductors 3 and 4 with the line circuit 1 and 2 and comprises a step-by-step element 5 carrying a circuit controlling element 6, which step-by- 55 step element is normally held by means of a spring 7 against a stop 8. The arm 6 is

adapted to engage the contact element 9 when the step-by-step element has been moved the required distance, thereby to effect certain circuit changes as will presently appear. 60

At the central station I illustrate a battery 10 from which impulses may be transmitted over the line conductors 1 and 2 through the agency of the key 11. A slow acting 65 relay 12, slow acting by virtue of a copper shell 13 has an armature 14 carrying a pawl 15. Whenever the key 11 is sending impulses the armature 14 is attracted and remains attracted until the cessation of the 70 impulses. This is due to the fact that the magnet 12 is slow acting and while it attracts its armature with the first impulse it does not release its armature as the interval between succeeding impulses of a call is not 75 sufficient to permit the armature 14 to be released, the armature 14 thus remaining attracted until the circuit through the key 11 is broken and remains broken. A magnet 16 serially associated with the magnet 12 80 controls an armature 17 carrying a pawl 18 and this magnet 16 actuates its armature 17 in accordance with each impulse. Thus the first impulse permits both pawls 18 and 15 to be placed in connection with the step-by-step element 5, the pawl 15 acting as a holding pawl and the element 5 moves in response to impulses received in accordance 85 with the movements of the armature 17. 90

When the step-by-step element 5 has been moved the required distance in order that the arm 6 engages the spring 9, then a circuit is established through the magnet 19 which thereupon attracts its armature 20. The armature 20 carries a flexible spring 95 21 adapted to engage a contact 22. The contact 22 is associated with a local signal 23, the other terminal of said local signal being connected by means of the conductor 24 with the arm 6. Whenever the arm 20 is attracted the element 21 does not immediately engage the contact 22 because this element 21 being flexible may bend and the element 21 is prevented from moving immediately in response to the movement of the armature 20 through the agency of a dash pot 25, which dashpot only permits the elements 21 and 22 to engage after the magnet 19 has been energized a sufficient length of time. The time between succeeding impulses, as when the arm 6 only passes the contact 9 without stopping there, is not 100 105 110

sufficient to permit the dash pot 25 to release the spring 21 and thus contact is not made between the elements 21 and 22 under such conditions. Whenever a station is to be called, however, then the circuit through the key 11 is closed and remains closed for a certain period of time after the elements 6 and 9 of the particular station desired have contacted, thus to allow the dash pot 25 to release the element 21 so that it may engage the contact 22 to thereby operate the local signal 23. This dash pot 25 is set forth more in detail in Fig. 2 and comprises a cup shaped casing 26 having in its base a small bleeder port 27 and having as a cover a flexible diaphragm 28 secured by means of an airtight joint to the upper rim of the cup 26 by means of the annular collar 29 and the screws 30. A plunger 31 suitably controlled by the diaphragm 28 by means of the two plates 32 and 33 is pivotally associated at 34 with the spring 21. Now when the armature 20 is attracted the air cannot enter the interior of the dash pot rapidly enough through the bleeder port 27 to permit the diaphragm 28 to move vertically in response to the pull exerted by the armature 20, but this movement of the diaphragm and the consequent movement of the element 21 takes place gradually so that contact between elements 21 and 22 is established only after a certain time interval. In this way an effective slow acting element is provided to control the final circuit closure of the substation signal circuit after the other elements of the signal receiving device have been placed in their proper signal receiving condition. The circuit through the magnets 12 and 16 may be traced as follows: line conductor 2, conductor 4, magnet 16, conductor 34, magnet 12 and conductor 3 to the line conductor 1. The circuit through the magnet 19 may be traced from line conductor 1, conductor 3, conductor 35, magnet 19, element 9, arm 6, conductor 36, armature 17, contact 37, conductor 38, conductor 4, to the line wire

2. The circuit through the signal 23 may be traced from line conductor 1, conductor 35, armature 20, contact spring 21, contact 50 22, signal 23, conductor 24, arm 6, conductor 36, armature 17, contact 37, conductor 38, conductor 4, to the line conductor 2.

I have herein shown a specific form of carrying out my invention, but this specific form is not intended to limit the invention to this particular form, as many modifications within the scope of the appended claims may be made, but

Having thus described one form of carrying out my invention, what I claim as new and desire to secure by Letters Patent is:

1. In a substation signal-receiving apparatus, the combination of a step-by-step element, a stepping magnet therefor, holding means for said element, a magnet therefor, a signal circuit open at two points, one of which is closed by said stepping means, an electro-magnet and a circuit therefor adapted to be closed by said step-by-step element, means for sluggishly closing the second point of the signal circuit, controlled by said magnet.

2. In a substation signal-receiving apparatus, the combination of a step-by-step element, a stepping magnet therefor, holding means for said element, a magnet therefor, a signal circuit open at two points, one of which is closed by said stepping means, an electromagnet, a circuit therefor adapted to be closed by said step-by-step element, and an armature for said magnet adapted to respond sluggishly to said magnet whereby said signal circuit is closed only after a notable length of time after the closing of said last circuit.

In witness whereof, I hereunto subscribe my name this 6th day of December, A. D., 1911.

HARRY O. RUGH.
